[57] CLAIM

The ornamental design of an animal curry brush, substantially as shown and described.

DESCRIPTION

FIG. 1 is a top plan view of an animal curry brush showing my new design;

FIG. 2 is a bottom plan view thereof;

FIG. 3 is a side elevational view thereof showing the gripping tab in a raised position, the opposite side being a mirror image of the side shown; and

FIG. 4 is a top perspective view of FIG. 3. The fragmentary broken line showing of a hand in FIG. 4 is for purposes of illustration only.

FIG. 1

FIG. 4
